UNITED STATES PATENT OFFICE.

WILLIAM GOESSLING, OF ST. LOUIS, MISSOURI.

DESIGN FOR A NAIL-CLEANER.

SPECIFICATION forming part of Design No. 25,702, dated June 30, 1896.

Application filed February 1, 1896. Serial No. 577,753. Term of patent 7 years.

To all whom it may concern:

Be it known that I, WILLIAM GOESSLING, a resident of St. Louis, in the State of Missouri, have invented and produced a new and original Design for Nail-Cleaners, of which the following is a full, clear, and exact description, reference being had to the accompanying drawings, forming a part thereof.

Figure 1 is a top plan or face view of my complete device, showing the design. Fig. 2 is a side or edge view of the same, the two views being deemed necessary to fully illustrate my design.

The feature of my design consists of a piece of material formed in such design as to have one end, A, pointed and the other end, B,

formed with a rounded point. The point at the end A is thinner than the remaining portion of the strip, as shown by C, and tapers to a sharp point. At the point where the taper begins it forms a semicircular curve D.

Having fully described my design, what I claim is—

The design for a nail-cleaner as herein shown and described. 25

In testimony whereof I affix my signature in the presence of two witnesses.

WILLIAM GOESSLING.

Witnesses:

ALFRED A. EICKS,
J. C. PETIT.
